UNITED STATES PATENT OFFICE.

JOHN H. UHRIG, OF BEVERLY, NEW JERSEY, ASSIGNOR TO UNITED STATES CAST IRON PIPE & FOUNDRY COMPANY, OF BURLINGTON, NEW JERSEY, A CORPORATION OF NEW JERSEY.

CENTRIFUGAL MOLD.

Application filed February 21, 1923. Serial No. 620,330.

To all whom it may concern:

Be it known that I, JOHN H. UHRIG, a citizen of the United States of America, and resident of Beverly, in the county of Burlington, in the State of New Jersey, have invented a certain new and useful Improvement in Centrifugal Molds, of which the following is a true and exact description, reference being had to the accompanying drawings, which form a part thereof.

My invention relates to centrifugal molds such as are used in the casting of pipe. Such molds are in practice cooled by a water jacket and have quite thick walls so as to be sufficiently rigid to retain their form under the exigencies of use. In operation, such molds are subjected to temperature conditions which put the inner portions of the mold under compression while the outer portions of the mold are under tension. These stresses tend to cause a wrinkling and upsetting of the metal on the inner surface of the mold and rapid heatings and coolings may cause these wrinkled molds to crack open and develop fissures. The tendency to develop fissures under the described conditions is particularly marked in case of a pipe mold having an enlarged end such as a bell and at the enlarged portion of the mold and it is found in practice that the bell ends of the mold have a much shorter useful life than the cylindrical portions of the mold. The object of my invention is to provide a mold which will be, to a large extent, free from upsetting strains which develop fissures, and my invention consists, generally speaking, in forming a centrifugal mold of an outer, comparatively thick wall tube and an inner thin wall tube, the outside conformation of which, at least in the operations where the mold is normally subject to the greatest strains, is of such dimensions as to leave a small clearance space between the inner and outer members when both are cold while, when the inner member is heated by molten metal in forming the casting it will expand into contact with the outer member. By reason of this construction, the inner member can and will expand freely when first heated by the molten metal without having its inner surface subjected to upsetting strains, while, after coming in contact with the outer member, it will be energetically cooled and at all times will be

comparatively free from the upsetting stresses which bring about the formation of fissures. As the deformation and formation of fissures is most apt to occur in the bell or enlarged end of the mold it will ordinarily be sufficient to provide the bell end of the mold with the independently expandible inner member though obviously the inner member in one or more sections can be made to extend through the entire length of the mold with advantage.

The nature of my invention and various features of construction which I consider advantageous will be best understood as described in connection with the drawings in which—

Figure 1 is a longitudinal sectional elevation of the mold embodying my invention, the central portion of the mold being broken away.

Figure 2 is an end view of the construction shown in Fig. 1, viewed from the right hand end, and

Figure 3 a detail view illustrating a modification.

A indicates the outer member of a bell end pipe mold having, as shown, a seat portion indicated at A' in the rear of its bell portion indicated at A². A³ is the terminal flanged end of the mold member and A⁴ the terminal flanged left hand end of the mold member ending, as shown, in a circular flange A⁵. B is the casing surrounding the mold and forming a water jacket for cooling the mold member water-tight joints being indicated at C, C, etc., the casing having the end formation indicated at B', B² and B³, so as to form joints for the flanges A³ and A⁴ of the member A. D is the ordinary core ring used to support the core H, the core ring having an inner face D' which comes directly in contact with the inner mold member as will be described. As shown, the core ring D is supported in a ring E which fits in a seat A⁶ of the outer mold member and forms an extension of an end plate E' having circumferential flanges E² and E³ as indicated, the outer circumferential flange E³ serving, if desired, as a driving pulley or gear. F⁴, F⁴, indicate wedge openings formed in the wall E² and end plate E', the end plate being secured in position through bolts G secured to the flanged end of the member A extending through openings in the end plate E' and provided

with nuts G' and spring plate G^2 so that the end plate is held in position on the outer mold member by yielding elastic means. F, F , are wedges driven into the wedge openings E^4 and operating to hold the core ring D in position in the seat member E .

I is an annular ring secured to the left hand end of the member A by bolts J , nuts J' and springs J^2 , the portion I' of the annular ring I preferably fitting on the inside of the member A , as indicated, and being preferably somewhat inclined, as shown. K indicates the end of the pouring runner through which the molten metal is introduced into the mold. L indicates an inner mold member which, as shown, is of such dimensions as to extend over the bell end of the mold and somewhat beyond the bell end where, by preference, I form it with a seat portion L' adapted to form a close fit with the seat portion A' of the mold member A while the enlarged or bell portion of the inner member which is of relatively small thickness compared with the outer member A has such outside conformation that it will when both mold members are cooled not come in contact with the enlarged portion A^2 of the outer member but leave a space between the inner and outer members which, however, is closed and both members brought into contact with each other throughout their length when the inner member is heated by the molten metal poured into the mold. As shown, and by preference, I form the inner member with a terminal flange L^4 which fits against a seat A^7 of the outer member, as shown, and also fits against the seat portion D' of the core ring.

In the modification shown in Figure 3, the inner mold member L is shown as only extending slightly beyond the enlarged or bell end of the outer mold member and as abutting against a solid portion of the mold member A . In the construction of Figure 1, however, I have illustrated a combination of the inner mold member, preferably in a separate section throughout the length of the mold, this inner member extension being indicated at L^5 and being formed with conical ends L^6 and L^7 which fits against conical end surfaces L^2 and I' , this construction tending to center the portion L^5 of the inner member when both mold members are cold and the inner member L^5 , therefore, out of contact with the inner surface of the outer mold member.

It will be observed that I have provided for the independent longitudinal extension of the inner mold member by making the abutting portions of the mechanism elastically yielding; in the one case the springs G^2 permitting the core ring seat E and other parts to move outward under a longitudinal thrust and, in the other case, the springs J^2 permitting the angular ring I to move

outward under longitudinal thrust of the inner mold member. In cases where the section of the inner mold member, such as section L , is comparatively short, there will ordinarily be sufficient elastic yielding in the wedges F to permit of the necessary longitudinal extension of the mold member when requiring the use of the springs G .

Having now described my invention, what I claim as new and desire to secure by Letters Patent, is:

1. A centrifugal mold comprising an outer metallic tubular member with comparatively thick walls and an inner thin walled metallic tubular member the external diameter of which is less than the inner diameter of the outer member when both members are cold and so proportioned that the inner member will contact with the outer member when said inner member is expanded by the heat of a charge of molten metal.

2. A centrifugal mold comprising an outer metallic tubular member with comparatively thick walls and an inner thin walled metallic tubular member the external diameter of which is less than the inner diameter of the outer member when both members are cold and so proportioned that the inner member will contact with the outer member when said inner member is expanded by the heat of a charge of molten metal, in combination with an elastically yielding abutment for the inner member.

3. A centrifugal mold comprising an outer metallic tubular member with comparatively thick walls and an inner thin walled metallic tubular member the external diameter of which is less than the inner diameter of the outer member when both members are cold and so proportioned that the inner member will contact with the outer member when said inner member is expanded by the heat of a charge of molten metal, in combination with means for water cooling the outer member.

4. A centrifugal mold comprising an outer metallic tubular member with comparatively thick walls and an inner thin walled metallic tubular member the external diameter of which is less than the inner diameter of the outer member when both members are cold and so proportioned that the inner member will contact with the outer member when said inner member is expanded by the heat of a charge of molten metal, in combination with means for water cooling the outer member and an elastically yielding abutment for the inner member.

5. A centrifugal pipe mold for pipes having enlarged ends comprising an outer metallic tubular member with comparatively thick walls and an enlarged end, and an inner thin walled metallic tubular member having also an enlarged end the outer conformation of which is such as to leave a

- clearance between it and the enlarged end of the outer member when both members are cold and to contact with such outer members when the inner member is heated and expanded by a charge of molten metal.
6. A centrifugal pipe mold for pipes having enlarged ends comprising an outer metallic tubular member with comparatively thick walls and an enlarged end, and an inner thin walled metallic tubular member having also an enlarged end the outer conformation of which is such as to leave a clearance between it and the enlarged end of the outer member when both members are cold and to contact with such outer member when the inner member is heated and ex-
- panded by a charge of molten metal, said inner member having a seat portion of such diameter as to form a close fit when cold with a seat in the outer member located in 20 the rear of its enlarged end.
7. A centrifugal mold comprising an outer metallic tubular member with comparatively thick walls, an inner thin walled metallic tubular member fitting loosely in the 25 outer member and yielding elastic abutment for the inner member whereby said inner member is given freedom to expand longitudinally independently of the outer member.

JOHN H. UHRIG.
